CLAIM

The ornamental design for a flexible electronic device holder, as shown and described.

DESCRIPTION

The flexible electronic device holder is for holding electronic devices such as I-Pods, MP3 Players or cell phones.

FIG. 1 is a front, top, left side perspective view of a flexible electronic device holder, embodying my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line showing in FIG. 1 of an electronic device positioned on the flexible electronic device holder is for illustrative purposes only and forms no part of the claimed design.
